UNITED STATES PATENT OFFICE.

JOSEPH O'BYRNE, OF CHICAGO, ILLINOIS, ASSIGNOR OF ONE-THIRD TO
JOHN F. MAHON, OF SAME PLACE.

TRAP FOR SINKS, &c.

SPECIFICATION forming part of Letters Patent No. 511,646, dated December 26, 1893.

Application filed December 12, 1892. Serial No. 454,965. (No model.)

To all whom it may concern:

Be it known that I, JOSEPH O'BYRNE, a citizen of the United States, residing at Chicago, in the county of Cook and State of Illinois, have invented a new and useful Sanitary Vertical Trap for Sinks, Washbowls, Bath-Tubs, &c., of which the following is a specification.

My invention relates to improvements in traps for sinks, wash-bowls, bath-tubs, &c., and the objects of my invention are, first, to prevent, by means of an automatic or self-closing valve, the escape of sewer gas into the apartment in which the sink, bowl, or tub is situated; second, to disinfect the waste pipe, and destroy the disease germs engendered therein by marsh or sewer gas. I attain these objects by the mechanism illustrated in the accompanying drawings in which—

Figure 1 is a perspective view of the entire trap; Fig. 2, a vertical section of the entire trap, showing the various parts in position; Fig. 3, a section in perspective of the hollow ring for holding the disinfectant; and Fig. 4, the bottom of said ring, showing the screws by which it is attached to the upper portion of the same.

Similar letters refer to similar parts throughout the several views.

The trap is composed of three parts, the cylinder B of glass or other suitable material; the cover for the same A, containing a chamber for holding camphor or other disinfectant, and the mechanism for operating the automatic valve f; and the lower portion of the trap designated by the letter C, containing the automatic gate-valve.

E is a hollow ring, designed to contain a disinfectant, and placed in the cylinder B, as shown in Figs. 1 and 2. This ring is shown in detail in Figs. 3 and 4, the slots to allow the water to percolate the disinfectant being designated by the letter h in said figures, and the screws by which the bottom portion of said ring is attached to the top being designated by the letter g.

The automatic valve consists of a ball f, capable of turning on its axis d, and is held in

position at the end of the flush tube by means of the spring s operating upon the piston rods 50 c—c, said spring being coiled around the flush tube in the spring box b, which is hermetically closed by means of the cap i. The spring s is so adjusted as to sustain from three to four ounces of water in the flush 55 tube. The valve is opened by means of the water running through the flush tube, and is closed by the pressure of the spring s when the weight of water in said tube falls to three or four ounces.

The dotted lines in Fig. 2 show the ball valve f and also the gate-valve e open. This latter valve also acts automatically closing by its own weight after the passage of the water. I am aware that there is no novelty 55 in the use of this gate-valve e, and make no claim therefor, except as part of my trap.

The space a in the cover A, Fig. 2 may be used as a chamber for holding disinfectants to destroy the odors arising from decaying 70 wood, &c., in the sink-box.

The various parts of the trap are connected with each other by means of the screw threads on each, shown in the accompanying drawings, and together form an effective trap for 75 the prevention of the escape of sewer gas, and which may be connected at its upper end by means of couplings to the sink or wash-bowl, and at its lower, by the same means to the waste-pipe.

What I claim, and desire to secure by Letters Patent, is—

1. In a vertical trap, the combination, with a cylindrical case or tube, of a horizontally rotatable spherical valve, suitably balanced 85 and maintained at the lower end of the said tube by means of a single spring balance coiled around said tube, a hollow ring for holding disinfectants, and a vertical gate-valve, all inclosed in an air-tight chamber, 90 substantially as described.

2. A sanitary vertical trap consisting of an air-tight chamber containing the automatic valve hereinbefore described, a hollow slotted ring for holding disinfectants, and a lower 95 gate-valve substantially as described.

3. In a vertical sink trap, the combination of the ball valve *f*, rotatable horizontally on its axis *d*, the single coiled spring *s* for maintaining said valve *f* in position at the end of the flush tube *F*, the box *b*—*b* inclosing the spring *s*, the hollow slotted ring *E* for holding disinfectants, and the gate-valve *e*, ar-

ranged and operating as and for the purposes set forth.

JOSEPH O'BYRNE.
